UNITED STATES PATENT OFFICE.

HARRY C. BERRY, OF SPOKANE, WASHINGTON.

ELEVATED RAILWAY.

1,361,809.

Specification of Letters Patent. Patented Dec. 14, 1920.

Application filed January 29, 1920, Serial No. 354,814. Renewed October 27, 1920. Serial No. 419,993.

To all whom it may concern:

Be it known that I, HARRY C. BERRY, a citizen of the United States, residing at Spokane, in Spokane county and State of Washington, have invented certain new and useful Improvements in Elevated Railways, of which the following is a specification.

My present invention relates to improvements in elevated railways of the suspended type, utilizing electricity as the preferred propelling power, and designed especially for passenger traffic, but also adaptable for use in the transportation of freight and other commodities.

15 The primary object of the invention is the provision of a railway structure and its rolling stock in which the cars or carriages are well balanced for rapid transit and smooth passage, and supported or elevated upon a 20 stable and rigid superstructure along which they may be propelled with despatch, and to this end the invention consists in certain novel features of construction and combinations and arrangements of parts as will be 25 hereinafter set forth and claimed.

In the accompanying drawings I have illustrated one complete example of the physical embodiment of my invention in which the parts are combined and arranged 30 according to the best mode I have thus far devised for the practical application of the principles of my invention.

The invention as exemplified in the drawings is subject to colorable changes and alterations within the scope of my appended claims, without departing from the spirit of the invention, and such changes and alterations are contemplated in the physical adaptation of the invention to actual use.

40 Figure 1 is an enlarged, transverse, sectional view through one of the cars and illustrating, in cross section the railway structure.

45 Fig. 2 is a view in side elevation showing the elevated railway and suspended car, part of the car being broken away to disclose in section the interior of the same, for convenience of illustration.

50 Fig. 3 is a detail view, showing in section one of the lateral guide wheels and its connection with the side of a car.

In the preferred form of the invention as 55 illustrated in the drawings, the elevated superstructure for the railway is supported on the base ties or cross stringers 1 of concrete, and spaced at suitable and regular inter-

vals, just beneath the surface of the road bed, and from these stringers are erected the ferro-concrete posts 2, 2 arranged in pairs and connected by the transverse arch or girder indicated as a whole by the numeral 3. The arch or girder 3 is made up of metal beams, plates, and braces, bolted together in approved manner to form a rigid and well braced structure, as indicated in dotted lines 60 Fig. 1, and these successive arches are connected by longitudinal spans S of fabricated metal as shown in Fig. 2, to furnish a suitable and workmanlike structure for supporting and suspending the rolling stock or trains 65 70 passing through the structure in traffic.

Preferably the transverse arches or girders 3 are covered with a housing 4 for protection against the elements of the weather and the underside of the girder is recessed to accommodate the rail structures and truck structures as well as the electric conductors and trolleys, as shown in Fig. 1.

The railway track stringers 5, 5, are made up of longitudinal channel irons forming continuous stringers between the adjoining arches of the superstructure, and these stringers are secured to the arch or girder at the sides of the recessed underside of the arch by bolts or other securing devices with 80 85 the channel flanges directed outwardly. Against the outer faces of the stringers the track rails 6, 6, are attached by the rail fasteners or cleats 7, 7, said rails forming the track for the traffic and being located in upright position as usual. The rails are of the usual or standard railroad type, and are rigidly and securely supported by their fasteners and channel stringers from the superstructure of the viaduct, the fasteners being 90 95 located at regular intervals and spaced the proper distance apart to establish a wide margin of safety in the transportation of loads over the rails.

A suitable distance above the ground surface are arranged a pair of complementary side rails 8, 8, forming lateral guides for the purpose to be described, and bolted to the uprights or posts of the viaduct to form a continuous smooth track, in a vertical plane 100 at each side of the center of the railway. At the uppermost point of the arched recess R, which recesses R form a clere-story in the superstructure or viaduct, and central of the clere-story, is supported the electric conductor 9 in the usual form of an overhead trolley wire as in electric railways, and the 105 110

necessary line wires for completing the circuits are carried in the viaduct in customary manner and extend to the power house and generators required for the purpose.

5 As before stated the railway is adapted for either or both passenger and freight traffic, and for purposes of illustration I have used a passenger type of car, indicated as a whole by the numeral 10, and shown to be cylindrical in form with the pointed front or forward end 10' and the rear or hind end 10" formed of frusto-conical shape with the extremities open at front and rear. The car or carriage is of proper and convenient dimensions, and is preferably fashioned with an outer wall 11 made up of metal plates of convenient size and dimensions, and an inner shell of veneer as 12 is spaced within the outer wall, there being suitable braces and connections between these members, and the interior of the car is also braced, in addition to other means, by the flat floor 13 elevated a suitable height above the lower portion of the car, and providing a commodious interior for the passenger car. The usual necessary features as windows, seats, baggage racks &c are a part of the interior equipment of the car, and the exit and entrance doors D D for the car are located at the sides near the ends, there being ventilators or manhole openings 14, 14 in the roof of the car convenient for access.

The suspending and supporting trucks for the car are located on the rounded roof portion thereof, and comprise the vertical spaced pedestals 15, 15, firmly and rigidly affixed to the car frame, having journal bearings 16 for the axle 17, and at the ends of the axle are fixed the flanged wheels 18, thus completing a two wheel truck supported on the track rails 6, 6. The required number of these trucks is carried at the top or roof of the car, and one of the trucks, as 19 at the forward end of the car may be a motor truck, driven from the electric motor 20 in the interior of the car and secured at the ceiling thereof, the required gear between the truck and motor being indicated at 21. The current is taken from the conductor or trolley wire by the trolley wheel 22, and the electrical connections are controlled by the trainman in the forward compartment C partitioned off in the front end of the car. The car is propelled by the electric motor in usual manner, the power being transmitted to the motor truck from the motor under control of the motorman or trainman, and the car which is suspended from its several trucks on the rails or tracks is swiftly driven forward under the electric power.

To prevent lateral swaying of the car, side wheels 23, 23 are utilized, projecting horizontally from the sides of the car below the central longitudinal axis thereof, and the wheels are in position to travel over the

side tracks 8, 8, that are arranged in vertical planes and supported on the posts of the viaduct at each side thereof.

The wheels 23, are supported in resilient brackets 24 made of outwardly curved metal plates having supporting ears 24' for the wheel 23, and these brackets are disposed longitudinally of the car, with their slotted ends 25 retained by the front and rear headed bolts 26, 26 which permit the resilient plate 24 to be flexed toward the car, and end stops 27, 27 are provided beyond the ends of the bracket to prevent excess movement of the bracket. Thus, as the car is, of necessity, given freedom for forward movement on its trucks, lateral swaying or movement of the car is prevented in excess of requirements, and the resilient brackets with the wheel contact on the side rails absorb shocks and prevent undesirable lateral motion of the car so that it may progress with a steady and smooth movement.

In order to reduce atmospheric resistance at the front or forward end of the car, a tubular passage, extending longitudinally from end to end thereof, is provided beneath the floor of the car, forming an air duct, with a suction fan 29 at the central forward opening 30, and the outlet rear end 31 also located on the central longitudinal axis of the car. The purpose of the fan and duct is to draw the atmosphere from in front of the car, thus reducing the resistance of the air to the moving car, and pass the currents of air through the duct and out through the rear outlet. The fan impels the air through the duct at a greater velocity than the air currents pass the outside of the car and thus the resistance at the front end of the car is reduced, while the air passing out through the rear central outlet 31 prevents the formation of a vacuum and consequent with its retardation of the car.

Having thus fully described my invention, what I claim as new and desire to secure by Letters Patent is—

1. The combination with the supporting viaduct and overhead suspension rails, of a car having trucks supported on said rails, and electric propelling means including a motor truck, lower track rails on the viaduct, and lateral guide wheels on the car engaging said lower track rails, said wheels having resilient supports comprising slotted brackets and headed bolts retaining the brackets in position so that they can flex as described.

2. The combination with the supporting rails of a car having trucks comprising upright, overhead spaced pedestals, axles journaled in the pedestals and flanged wheels on the outer ends of said axles, one of said trucks being an electrically propelled motor truck, lower side tracks, and said car having resiliently cushioned guide wheels adapted to engage said lower side tracks.

3. The combination with the supporting tracks, of a car and suitable propelling means therefor, said car being cylindrical in shape with pointed ends, and provided
5 with a flat floor, an air duct extending longitudinally of the car beneath the floor and having an inlet and an outlet on the line of the longitudinal axis of the car, and a fan blower at the front of the duct for directing air currents through said duct and out 10 at the rear, for the purposes described.

In testimony whereof I affix my signature.

HARRY C. BERRY.
